UNITED STATES PATENT OFFICE.

WILLIAM L. KUBACH AND EVAN J. EDWARDS, OF CLEVELAND, OHIO, ASSIGNEES TO
GENERAL ELECTRIC COMPANY, A CORPORATION OF NEW YORK.

ELECTRIC-CIRCUIT-CONTROLLING DEVICE.

1,194,194.

Specification of Letters Patent.

Patented Aug. 8, 1916.

Application filed February 23, 1915. Serial No. 9,812.

To all whom it may concern:

Be it known that we, WILLIAM L. KUBACH and EVAN J. EDWARDS, citizens of the United States, residing at Cleveland, county 5 of Cuyahoga, State of Ohio, have invented certain new and useful Improvements in Electric - Circuit - Controlling Devices, of which the following is a specification.

Our invention relates to devices for use in 10 electric lighting circuits for the purpose of preventing the consumer from using more than a fixed amount of current. Devices of this character are especially adapted for use where the lighting consumer pays a flat rate. 15 It is desirable that when the consumer exceeds a specified amount of current the lamps in the circuit be caused to flicker, thus producing a disagreeable condition which can only be removed by cutting out 20 the lamp or other device which takes the extra current.

Our invention comprises a device which is adapted to be inserted in the supply circuit and which comprises an electro-magnet 25 or solenoid, which, by its action upon a suitable armature, causes contacts to be separated, thus breaking the circuit, and after a suitable interval causes the said contacts to reengage, thus completing the circuit. This 30 operation is repeated comparatively rapidly, but the device is so constituted that the circuit is interrupted for an appreciable interval. This operation is to be distinguished from a rapid vibration which would 35 not cause an appreciable flicker and also from a long break which would leave the room in darkness for a considerable time.

One of the advantages of our invention over devices which have been heretofore 40 proposed is that it includes a minimum number of contacts, thus securing a more certain make and break and lessening the chances of faulty operating arising from wear and accumulations between the contacts. Our device also includes checking 45 means which come into operation both on the break and make and thus reduce pounding in the device. Another advantage arises from the fact that the solenoid comprised by our device has a continuous winding, thus facilitating trouble finding as well 50 as reducing the cost of manufacture over that required for a device comprising a split coil. It is also to be noted that in our construction the weight of the movable contact 55 and attached parts is such that the contact pressure is comparatively great, thus insuring a good contact and tending to remove any possible corrosion. Also the chance of the movable parts sticking is reduced by this 60 construction. These and other features and advantages of our invention will appear from the accompanying drawing and from the description thereof which follows.

In the drawings, Figure 1 is an elevation, 65 and Fig. 2 a sectional elevation of a device embodying our invention.

The device illustrated is of the same general character as that covered by Doane application Serial No. 834,259, filed April 24, 70 1914, and assigned to the same assignee as is the present invention. Like the device described in the said application, the present device comprises a bulb or other casing 10 provided with a base 11, which may be 75 of the Edison type. The device is adapted to be inserted in an ordinary incandescent lamp socket and to be placed in series with the lamps or other load. The leads 12, 13 are sealed in as in the case of incandescent 80 lamps. The device shown is adapted to be disposed vertically. It includes the metal plate 14, which rests at the bottom of the bulb, and carries the contact 15, which may be of silver and which may be removably 85 held in the plate 14, as shown in 16. The plate 14 is attached by metal straps 17 to the metal plate 18, which supports an insulating washer 19, upon which rests the solenoid 20. The straps 17 may extend 90 through the plate 18 and serve to support the metal plate 21 upon the top of the solenoid, which is separated by the insulating washer 22 from the said solenoid. A terminal post 23 is supported on and is in electrical contact with the plate 21 and is, therefore, electrically connected to the contact 15. The terminal post 23 is connected to the lead 13. The other lead 12 is connected to a terminal post 24, which is supported by 100 the insulating washer 22 and is electrically connected with the winding of the solenoid.

20. The solenoid carries at its center and suitably insulated therefrom, a casing or sleeve 25. This extends above the solenoid and carries at its upper end in a suitable 5 channel the trough shaped insulator 26, which engages the end of glass tube 26' and serves to hold the parts of the device in alinement therewith and to support and guide the flexible conductors 27, 28, which 10 connect the leading-in wires with the posts 23 and 24 respectively. Slidable within and closely fitting with the sleeve 25 is the hollow, and preferably tubular, member 29, which carries at its lower end the contact 30. The said contact is electrically connected with the winding of solenoid 20 by the flexible conductors 31, which are wound in reverse directions around the outside of the tube 29. This reverse winding is for 15 the purpose of preventing the rotation of the tube 29 to any appreciable extent, as such rotation might cause the contact 30 to fit poorly with the contact 15. The tubular member 29 is closed at the top 32 and contains the loosely supported iron core or armature 33, which is drawn upwardly by the solenoid 20 upon the passage of an abnormal current through the latter. The top 20 portion of the sleeve 25 is provided with the valve chamber 34 having a valve 35 therein which controls the communication therewith and the sleeve 29. A restricted outlet 36 is provided from said valve chamber and extends laterally through the cap 37 for the 25 sleeve 25.

In operation the above described device is included in series with an electric circuit. The device is so calibrated that the contacts 15 and 30 remain in engagement during the 30 normal operation of the circuit. Upon an increase in the load beyond that for which the instrument is calibrated and that for which the consumer has contracted, the armature or core 33 is drawn up by the solenoid 20 and strikes the top 32 of the tube 29, thus causing the contact 30 to be instantly separated from the contact 15. The blow which is struck the end 32 causes the tube 29 to be raised in the sleeve 25. On 35 account of the close fit of the tube 29 with the sleeve 25, the tube 29 will be cushioned by the air which will accumulate in the upper part of sleeve 25, a limited amount of which can get out through the passage 36 by reason of the valve 35. Upon the descent of the contact 30 and attached parts, the travel thereof will be retarded on account of the close fit of the aforesaid parts 40 25 and 29, and on account of the seating of the valve 35. This will cause an appreciable time interval to elapse before the reengagement of the contacts and cause a decided flicker in the circuit. In order to prevent corrosion of the metal parts, and also to

insure the proper action of the valve, it is 65 preferred to fill the bulb with nitrogen or other inert gas.

Various changes and modifications of the above described structure will readily occur to those skilled in the art and are to be considered as coming within the scope of our invention. 70

What we claim and desire to secure by Letters Patent, is:

1. In a circuit controlling device, a substantially vertically disposed solenoid, a stationary contact beneath said solenoid, a hollow member slidably mounted in said solenoid and having at its lower end a contact normally held by gravity in engagement with said stationary contact, and a magnetic core within said member and adapted upon the passage of an abnormal current through said solenoid to strike said member and disengage said contacts. 75

2. In a circuit controlling device, a solenoid adapted to be substantially vertically disposed, a hollow member slidably supported in said solenoid and a core loosely supported upon the bottom of said member, the top of said member being so disposed as to be struck by said core upon the passage of an abnormal current through said solenoid, a stationary contact and a movable contact, and means whereby the latter is caused to follow the movement of the aforesaid hollow member. 90

3. In a circuit controlling device, a substantially vertically disposed solenoid, a tubular member slidably mounted in said solenoid, a core normally resting upon the bottom of said member and adapted to strike the top thereof upon the passage of an abnormal current through said solenoid, thereby moving the member upwardly in 100 said solenoid, a contact carried by said tubular member, and a stationary contact normally supporting said tubular member and the elements carried thereby. 105

4. In a circuit controlling device, a substantially vertically disposed solenoid, a stationary contact, a movable contact biased to engage said stationary contact, a hollow member slidably mounted in said solenoid and operatively related to said movable contact, and a magnetic core normally resting on the bottom of said member and adapted to strike the top thereof upon the passage of an abnormal current through the solenoid whereby said contacts are disengaged. 110

5. In a circuit controlling device a substantially vertically disposed solenoid, a stationary contact beneath said solenoid, a hollow member slidably mounted in said solenoid and having at its lower end a contact normally resting on said stationary contact, means whereby said contacts when separated are always biased to reengage, and 115 120 125

a magnetic core loosely mounted in said member and normally resting on the bottom thereof and adapted to strike the member and thereby move the member upwardly 5 upon the passage of an abnormal current through said solenoid thereby effecting the disengagement of said contacts.

In witness whereof, we have hereunto set

our hands this nineteenth day of February, 1915.

WILLIAM L. KUBACH.
EVAN J. EDWARDS.
